ELEVATED-CARRIER LATCH.

1,043,786.

Specification of Letters Patent.

Patented Nov. 5, 1912.

Application filed February 29, 1912. Serial No. 680,609.

To all whom it may concern:

Be it known that I, MALCOLM B. MOYER, a citizen of the United States, residing at Montevideo, in the county of Chippewa and 5 State of Minnesota, have invented certain new and useful Improvements in Elevated-Carrier Latches; and I do declare the following to be a full, clear, and exact description of the invention, such as will enable 10 others skilled in the art to which it appertains to make and use the same.

This invention relates to elevated carriers, and more especially to those employing a pivoted bucket; and the object of the same is 15 to provide an improved latching device for holding the bucket upright within the traveling carriage, which latch may be tripped by hand or by a trip mounted on a track. This object is accomplished by constructing 20 the latch and the catch therefor in the manner hereinafter more specifically described and claimed, and as shown in the drawings wherein—

Figure 1 is a side elevation showing the 25 parts of this improved device in position with the latch engaged with the catch to hold the bucket upright. Fig. 2 is a similar view with the bucket in vertical section showing the parts in the position they assume after the latch has been tripped so that the weight passes the center of gravity and rests upon the catch. Fig. 3 is a somewhat 30 similar view showing the bucket as turned slightly on its trunnions, and illustrating the catch as restoring the latch to its normal position. Fig. 4 is an end elevation 35 illustrating the position of parts as the bucket is being restored to its vertical position.

In the drawings is illustrated a bucket B having trunnions below its center of gravity pivoted as at P in the arms of a yoke Y forming part of a carriage supported by 40 wheels W on an overhead track or cable C, and the letter T designates a trip attached to said cable for actuating the trigger herein-after described. No novelty whatever is 45 claimed for all these parts, as they are commonly employed in overhead carriers such as are used for conveying articles from point to point in the bucket, and dumping the latter when the point of delivery is reached. The dumping may be done by hand or automatically, and if done automatically the 50 trip T is set at a proper point upon the cable 55

C so that when the bucket reaches that point the trigger is engaged by the trip and the latch is moved to permit the bucket to dump. The trunnions of the bucket are pivoted at P below the center of gravity of the bucket 60 and its contents, and therefore the bucket must be connected in some manner with the yoke Y to prevent it from turning over undesirably, although such turning over becomes desirable when the bucket reaches the 65 point where it is to be dumped. The details of this latch mechanism form the subject matter of the present invention.

The latch proper consists of a short bar 1 pivoted at 2 across the yoke Y at a point 70 nearer its inner end or tip than its outer end or heel, and pivoted at its outer end at 3 to a rod 4 which leads thence upward and is pivoted at 5 to the trigger 6, which in turn is pivoted at 7 to a suitable support 8 75 on the frame so that its upper extremity 9 is in position to strike the trip T. This mechanism serves also as a stop for the latch, preventing the rise but permitting the descent of the tip of the bar 1. The parts 80 are so proportioned and the pivots so located that in their normal position the trigger stands upright and the bar 1 stands horizontal. Attached to the bar 1 in any suitable manner as by casting it integral therewith, is a weight 10 whose shape is immaterial although preferably it will be of the oval configuration shown in the drawings, so that it is narrower at the point 11 where 85 it joins the bar 1 somewhat outside of the main pivot 2, thus producing an acute-angled notch 12 at the inner side of the latch having a straight lower edge 13 and an inclined upper edge 14; and it is essential that this weight and the bar be so relatively disposed and pivoted that when the parts stand as seen in Fig. 1 the center of gravity will be between the two pivots 2 and 3 and the weight as a whole will stand upright while the bar as a whole stands horizontal. The 100 catch member of this improved latch mechanism consists essentially of a flat plate 15 (which may well be one leaf of an angle-iron) secured to and projecting beyond one end of the bucket B and standing on a chord 105 across the dotted circle 16 shown in Fig. 4 as struck around the pivot P, and at the center of the length of this plate is a notch 17. Said notch is deep enough to receive the tip of the bar 1 as shown in Fig. 1, but not 110

deep enough to receive the weight 10 when the parts stand as shown in Fig. 2; and the bar and weight are of proper size and the main pivot 2 properly disposed with respect to the pivot P to produce this condition. 5 All parts are by preference of metal and of the desired proportion, and details of construction, other than as described, are unimportant.

10 The operation of this improved latch is as follows: With the parts standing as seen in Fig. 1, the bucket B is prevented from tilting to either side because the notch 17 engages the inner end of the bar 1, and as 15 the weight 10 has passed outward beyond the main pivot 2 the center of gravity of the entire latch holds the parts in this position. The entire carriage and bucket may now be moved along the track or cable C on 20 which the wheels W travel freely, and when the point is reached where the bucket is to be dumped the latch may be actuated by hand or the trigger 6 may be moved by bringing it into contact with the trip T. 25 In either case the latch is turned from the position shown in Fig. 1 to that shown in Fig. 2, where the weight 10 moves beyond the center of gravity over the main pivot 2 and rests upon the plate 15 while the inner 30 end of the bar 1 moves out of the notch 17 so that the bucket is no longer latched. Being freed of restraint, the bucket (which is top heavy by reason of the low position of its pivots or trunnions P) turns to one 35 side or the other, and in doing so the plate 15 swings bodily around the center P so that its lowest point (its center, which is nearest the pivot P) is replaced by a point near one end which is higher or farther remote from 40 said pivot, and therefore the upper face of the plate 15 rides under the beveled upper edge 14 of the notch in the inner side of the latch and the latter is raised around its pivot 2. Fig. 3 illustrates the position of 45 parts at this time. Just as the higher end of the plate 15 passes out from under the weight and passes off from above the inner end of the bar 1, the entire latch stands on about its center of gravity and the momentum 50 imparted to it by the bucket—which will then be moving quite rapidly—causes it to pass said center of gravity and reassume the position shown in Fig. 1. The bucket now completes its half circle of rotation around its trunnions, and its load is 55 dumped. To restore the parts to their normal position, the operator swings the bucket back to the position shown in Fig. 1, and in doing so the high end of the plate 15 60 passes into the notch 12 and out of contact with either the upper edge 14 or lower edge 13 thereof until the bucket reaches the position shown in Fig. 4, and at this time the lower face of the plate 15 engages upon the 65 upper edge of the inner end of the bar 1 at

the point 13 and pitches the entire latch to about the position shown in Fig. 3 although the contact of the edge 14 with the upper corner of the plate 15 prevents the latch from tipping as far as shown in Fig. 2. 70 The parts are so proportioned that the latch in this action will not be tipped beyond its center of gravity, and hence when the notch 17 reaches a point vertically above the pivot P the weight 10 reassumes a vertical position and the inner end of the bar 1 rises into the notch 17, and the parts are again locked in the position shown in Fig. 1. Thus it will be seen that I have produced a latching mechanism which is entirely automatic in 75 its action in latching the bucket and which, when a trip T is employed, is also automatic in its action in unlatching the bucket; and yet I have avoided the use of any spring or adjustment, or other complications. The extreme simplicity of the device commands 80 itself to the user, and renders it unlikely to be affected by snow or sleet, or by dust or chaff if the bucket be employed for conveying articles of that character. 85

90 What is claimed as new is:

1. The combination with a support, a bucket pivoted below its center of gravity therein, and a catch consisting of a plate projecting beyond the end of the bucket and standing on the chord of a circle around its pivot, the plate having a notch in its outer edge; of a bar pivoted to said support with its tip normally engaging said notch, means for limiting the rise and permitting the descent of said tip, and a weight connected to said bar for holding the tip raised. 95

2. The combination with a support, a bucket pivoted below its center of gravity therein, and a catch projecting from the bucket and having a notch; of a bar pivoted to said support so that its tip may engage said notch, a stop for limiting the rise and permitting the descent of said tip, and a weight rigidly connected with and rising 100 from said bar and having its center of gravity in rear of the pivot thereof, for the purpose set forth. 110

3. The combination with a support, a bucket pivoted below its center of gravity 115 therein, and a catch consisting of a plate projecting beyond the end of the bucket and standing on the chord of a circle around its pivot, the plate having a notch in its outer edge at a point where said chord is nearest to the pivot; of a latch pivoted to said support and including a bar and a member rigidly projecting therefrom at an angle so as to leave between it and said bar a notch of sufficient depth to receive said plate, the 120 notch in the latter being of a depth to permit the passage of the tip of said bar but prohibit the passage of said member. 125

4. The combination with a support, a bucket pivoted below its center of gravity 130

therein, and a catch consisting of a plate projecting beyond the end of the bucket and standing on the chord of a circle around its pivot, the plate having a notch in its outer edge at a point where said chord is nearest to the pivot; of a latch pivoted to said support and including a bar and a weight rising rigidly from the bar at an angle so as to leave between it and said bar a notch of sufficient depth to receive said plate, the notch in the latter being of a depth to permit the passage of the tip of said bar but to prohibit the passage of said weight, a trigger pivoted to said support, and a flexible connection between the trigger and the outer end of the bar to check the turning of the latter on its pivot when its tip has engaged the notch in the catch.

5. The combination with a support, a bucket pivoted therein, and a catch consisting of a plate projecting beyond the end of the bucket and standing on the chord of a circle around its pivot, the plate having a notch in its outer edge at a point where said

chord is nearest to the pivot; of a latch 25 comprising a straight bar standing across said support and pivoted between its ends thereto and a weight rising rigidly therefrom and at right angles thereto and standing in rear of its pivot, the weight being 30 oval in contour so as to leave between it and said bar a notch of sufficient depth to receive said plate, the notch in the latter being of a depth to permit the passage of the tip of said bar but to prohibit the passage of 35 the weight through it, a rod pivotally connected with the outer end of said bar and rising therefrom, and means for checking the descent of said rod when the entire latch stands in a position where the tip of the 40 bar engages the notch in said plate.

In testimony whereof I have hereunto set my hand in presence of two subscribing witnesses.

MALCOLM B. MOYER.
